P. L. Hubbard

UNITED STATES PATENT OFFICE.

WILLIAM O. RENKIN, OF ORADELL, NEW JERSEY, ASSIGNOR TO QUIGLEY FURNACE SPECIALTIES CO., INC., A CORPORATION OF NEW YORK.

VALVE-OPERATING MECHANISM.

1,329,017.

Specification of Letters Patent. Patented Jan. 27, 1920.

Application filed November 22, 1918. Serial No. 263,694.

To all whom it may concern:

Be it known that I, WILLIAM O. RENKIN, a citizen of the United States of America, residing at Oradell, county of Bergen, State 5 of New Jersey, have invented certain new and useful Improvements in Valve-Operating Mechanism, of which the following is a specification.

My invention relates generally to the 10 semi-automatic operation of valves for controlling the flow of fluid masses and more specifically comprises a modification and simplification of the apparatus shown and described in my U. S. Letters Patent No. 15 1,301,167, dated April 22, 1919.

The best form of apparatus at present known to me as embodying my present invention is illustrated in the accompanying two sheets of drawings in which;

20 Figure 1 is a partially diagrammatic view of a sending station and multiple branch conduit and valves with my invention applied thereto, parts being shown in section and others broken away.

25 Fig. 2 is an enlarged detail of one of the valves and operating mechanism, and

Fig. 3 is a side elevation of Fig. 2.

Throughout the drawings like reference characters indicate like parts.

30 In the general system to which my invention is usually applied there is a blowing tank 1, from which graduated quantities of material are discharged by the use of compressed air, as in the manner set forth in the 35 pending application of Harry Arthur Kimber, Serial No. 214,755, filed January 31, 1918. The pulverized coal or other material so discharged from the supply tank 1, passes out through the main line conduit 5, to various branch storage bins.

In systems of the general construction above described, as heretofore operated, each operator at a branch or local station has been required to keep track of his local fuel 45 supply and, when the same approached exhaustion telephone into the supply station operator stating the amount of additional fuel required. The supply station operator when ready to deliver the amount required 50 at that particular station would telephone back to the local operator to set his switch valve 11, or 111, as the case might be, in the position which would close the main line conduit at that point and open the branch 55 connection 12 or 112 to the local storage bin.

The supply station operator would thereafter send the required amount of fuel through the main line of the system to the local bin in question and, when the supply had been delivered, telephone the local operator to close his switch valve and reopen the main line connection.

My present invention overcomes the delay and general awkwardness of the procedure above described by making the action of the 60 switch valves semi-automatic and controllable by the supply operator at the supply station through some such combinations of elements as are herein described.

On the axis of each switch valve, as 11, 70 is mounted a three armed lever 13, 113 or 213. The valves 11, 111, etc., are rotary two-way valves preferably of the construction shown and described in my pending application Serial No. 214,750, filed January 31, 75 1918. To the oppositely extending arms of each valve lever are connected pull-cords or chains, 15 and 28, or 115, 128, etc., by which the valve may be manually operated so as to rotate it into the position opening the line 80 conduit and closing the branch (see valve 111) or in the other position which closes the line and opens the branch (see valves 11 and 211). To the third and intermediate lever arm is connected a tension device, such 85 as coiled spring 27, 127 or 227, the other end of which is anchored to a fixed support such as the arm 6, 106 or 206, clamped to conduit 5, at the proper point to give the spring a tension sufficient to turn the valve 90 when free, into open-line and closed-branch position. Whenever the line is to be closed at any branch and the branch conduit, as 11, opened to fill the adjacent bin, the operator must pull on chain 28, 128 or 228 and further stretch spring 27, 127 or 227. To hold the valve in this position in spite of the continuing pull of spring I employ any suitable locking device such as a band brake 100 30, encircling pulley 29, on the valve spindle. One end of this band is made fast, as at 31, and the other is connected to the core of a solenoid 32, 132, or 232. A circuit, 33, 133 or 233, includes the coils of the corresponding solenoid and extends to the sending station where all circuits are energized 105 by current from any suitable source of supply connected to double pole switch 36. Each circuit also includes two circuit breakers or controllers, one of each pair, as 14, 110

114, or 214, being located near the valve, and branch to storage bin, while the other members of the pair, (35, 135 or 235) are located at the sending station.

- 5 The mode of operation of the present invention is substantially the same as that of the form described in my Patent No. 1,301,167, the pneumatic motors and controlling valves there shown having merely 10 been eliminated and the operator here manipulating the valve direct by pulling on chain 28. The operator closes circuit controller 14, 114 or 214, or makes sure it is already closed, before letting go of the 15 chain 28, 128 or 228. The other controller, 35, 135 or 235, for that circuit having been closed before the operator went out on his tour, the circuit 33, 133 or 233 is then completed and the solenoid energized to operate 20 the brake and hold the branch open against the pull of the valve spring. When the operator is sending from the supply station he opens circuit closer 35, 135 or 235 after filling any corresponding bin, thus 25 disabling the brake and allowing the spring 27, 127 or 227 to swing the valve back to line.

If any brake gets out of order, the spring can be disconnected and the valve operated 30 manually in both directions by chains 15 and 28, etc. If the spring goes out of action the manual operation also may be employed, circuit controller 14, 114 or 214, being opened to disable the brake.

35 In the drawings the valve 111 is shown in position for line, the supposition being that the operator has found that bin full, or its furnace out of operation, and consequently has left circuit controller 114 or 135 open. 40 The operator, after filling the first bin will then pull circuit controller 35, resetting valve 11 for line, and thus get connection straight through to valve 211, through which he can fill the third bin, and so on.

45 Other forms of valve locking and releasing mechanism could be substituted for the particular forms shown without modifying the principle involved in the invention.

Having described my invention, I claim:

- 50 1. In a system for the distribution of

fluid masses the combination, with a conduit, means for forcing fluid masses through said conduit, and a branch from said conduit located at a distance from the sending station, of a switch valve located 55 at the branch point, means for turning said valve in one direction operable from a point near the branch point, and means for turning it in the other direction controllable from the sending station.

2. The combination, with a main line conduit, a branch conduit, and a valve controlling the two, of means for constantly exerting a force tending to turn and hold said valve in one position, means for turning the 65 valve in the other direction located near said branch point, means for locking the valve in the first mentioned position, and connections for disabling said locking means extending to a distance from the branch 70 point.

3. The combination, with a rotary two-way valve, of a hand operated lever for placing said valve in one position, a spring constantly tending to place the valve in the 75 other position, a band-brake operatively arranged with reference to the spindle of said valve, an electro-magnet and armature arranged to apply tension to said band brake when the magnet is energized, an electric circuit including a source of electric current and the windings of said magnet, and a circuit controller also included in said circuit.

4. The combination, with a rotary two-way valve, of a hand operated lever for 85 placing said valve in one position, a spring constantly tending to place the valve in the other position, a band-brake operatively arranged with reference to the spindle of said valve, an electro-magnet and armature arranged to apply tension to said band brake 90 when the magnet is energized, an electric circuit including a source of electric current and the windings of said magnet, and two circuit controllers in said circuit one located near the valve and the other at a distant station from which the valve is to be 95 controlled in part.

WILLIAM O. RENKIN.
